UNITED STATES PATENT OFFICE.

ANDREW WONSOWICZ, OF GARY, INDIANA.

AUTOMATIC WEATHER STRIP.

Application filed January 6, 1926. Serial No. 79,667.

The present invention relates to weather strips, particularly adapted for swinging doors and windows. However, the invention is not limited for use in connection with the doors and windows of this type.

The object of the invention is the provision of means for automatically projecting a strip into engagement with the door or window frames, or into engagement with the sill, when such door or window is closed and to automatically retract said strip when the door or window is opened.

It is the further object of the invention to produce a weather strip of the above stated character which is economical to manufacture and simple to assemble and apply, with parts insuring definite and positive operation.

With the above and other objects in view the invention further resides in sundry details of construction, combination, and arrangement of parts hereinafter more fully described and pointed out in the appending claims.

In the drawings which show the preferred embodiment as at present devised:

Figure 1 is a fragmentary elevation of the swinging door or window, equipped with the weather strip of the present invention,

Figure 2 is a vertical section through the door or window as shown in Figure 1,

Figure 3 is a horizontal sectional view through the weather strip,

Figure 4 is a side elevation of one of the casing sections of the weather strip with the enclosed parts indicated by the dotted lines,

Figure 5 is a side elevation of the other casing section of the weather strip with the enclosed operating parts indicated with dotted lines, and

Figure 6 shows a side elevation of the completed weather strip.

Referring particularly to the drawings:

1 denotes a door or window to which the device is attached, the door or window having a panel 8 and being mounted to swing on the hinges 7 secured to the usual frame 6. On the upper and lower edges of the door or window is secured the weather strip of the present invention, which comprises a casing composed of two complementary elongated channelled strips 30 and 31, one designed to slide within the other to form an extensible casing. The end wall of the strip 31 is provided with a weather strip of felt, rubber or other material to engage with a

sill 3, or other surface of a door or window jamb or frame, to form a tight contact therewith. Suspended from the end wall of the casing member 30 are brackets 10 which receive the ends of the reciprocable rods 12 deposited in the casing. The rod may be additionally supported by rollers 19 mounted in a guideway 11 in which the rod 12 reciprocates.

The rod 12 has at spaced intervals openings or recesses 21 provided therein in which one arm of the bell-crank levers 14 engage, respectively. These bell-crank levers 14 are disposed within the casing formed by the channel strips 30 and 31, but are supported on pivot pins which extend through transverse elongated slots 20 in the side walls of the inner casing member 31 and mounted at their ends in the side walls of the casing member 30. Thus, by this construction the casing members are held in assembled position and the elongated slots 20 permit the casing to telescope one within the other to produce the desired expanding and retracting movement for the purpose of this device.

The other arm of the bell-crank levers 14 extend under a stop rod or pin 16 and are designed to engage the bow-leaf spring 15, one arranged adjacent each of said bell crank levers 14 and pivotally supported at one end to the bottom wall of the inner casing member 31.

The weather strip of this invention is designed to be inserted within a suitable groove provided in the edges of the door, as shown in Figures 1 and 2, and the outer casing 30 has its free ends bent laterally outward to provide flanges 32 which will receive nails or screws.

The weather strip above described is actuated by an adjustable presser head 5 forming a threaded extension from one end of the rod 12, preferably the end of the rod adjacent the hinge edge of the door or window. The coil springs 9 on the reduced ends of the rod 12 bear against the stationary brackets 10 to move and retain the operating parts of the weather strip in released or ineffective position. It will be obvious that as a door or window, equipped with the present invention, is closed the pressed head 5 will contact with the jamb and shift the reciprocating bar 12 against the action of the springs 9 and thereby swing the bell crank levers 14 so as to compress the springs 15, which ac-

tion will force the member 31 of the casing outwardly against the opposing wall of the door or window jamb or sill. The springs 15 acted on by the bell crank levers will produce a tight yielding contact with the surface which the packing or weather strip element 4 engages.

It will be observed and appreciated that the present invention can also be used upon 10 the side edges of doors and windows by providing the presser head 5 with a beveled or chamfered surface or permit the same to engage with an inclined surface.

The weather strip of the present invention 15 is a compact unitary device which may be readily applied as a unit in a groove of a door or window as the parts are permanently assembled together and contained in an extensible casing or housing.

Having thus described my invention, what 20 is claimed is:

1. An automatic weather strip for doors and windows comprising a casing of elongated complementary members, one adapted 25 to move transversely with respect to the other, a slidable bar within the casing and mounted longitudinally on one of the members, means for normally urging said bar to move in edgewise direction, a bow-leaf 30 spring within the casing having one end secured to the bottom of the other casing member, a bell-crank lever mounted within the casing and having one arm engaging an

abutment on said bar and the other arm engaging said spring member, a presser head 35 on said bar and normally extending beyond an end of said casing to engage with a jamb of a door or window, whereby the movable members of said casing will be moved outwardly when the door or window is closed.

2. An automatic weather strip for doors and windows comprising a casing of elongated complementary channel members, one adapted to move transversely with respect to the other, a slidable bar within the casing 45 and mounted longitudinally on one of the members, means for normally urging said bar to move in one endwise direction, a yieldable member within the casing and secured to the bottom of the other casing member, 50 spaced bell-crank levers disposed within said casing members and mounted on pivot members extending through transverse slots in the side walls of one of the casing members and supported on the side walls of the 55 other casing member, each of said levers having arms engaging an abutment on said bar and the other of said arms engaging said yieldable member, a presser head on said bar and normally extending beyond an end 60 of said casing to engage with a jamb of the door or window whereby the movable member of said casing will be moved outwardly when the door or window is closed.

ANDREW WONSOWICZ.
